UNITED STATES PATENT OFFICE.

WILLIAM E. WHITEHEAD, OF MILES PLATTIN, ENGLAND, ASSIGNOR TO
WHITEHEAD & ATHERTON MACHINE COMPANY, OF LOWELL, MASS.

MACHINE FOR OPENING AND OILING WOOL AND OTHER FIBROUS MATERIAL.

SPECIFICATION forming part of Letters Patent No. 240,484, dated April 19, 1881.

Application filed October 28, 1880. (No model.)

To all whom it may concern:

Be it known that I, WILLIAM E. WHITEHEAD, of Miles Plattin, England, have invented certain new and useful Improvements in
5 Machines for Opening and Oiling Wool and other Fibrous Material, of which the following is a specification.

My invention may be stated to consist in the combination, in a machine for opening fibrous material, with the first and other beaters and the lapping mechanism, of an oiler arranged and operating to administer oil to the material after it has passed the said beaters and immediately before it is wound into a lap. It has been customary, in some cases, to oil the material after it has been opened by a picker and loosely delivered on the floor, and in one instance it has been suggested for this purpose to place the oiler on the delivery end of the 10 picker. In other cases the wool or cotton has been spread on the apron of the carding-engine and there oiled. The latter plan is the one which generally has been followed. Under that method, however, one person at least is 15 required to attend every two cards. I, on the contrary, use one oiler to a lapper, which will prepare material for twenty-five cards, and these twenty-five cards will require the labor of but two persons. Further, by combining 20 the different parts of the machine as hereinbefore specified, I apply the oil after it has passed the first and other beaters and immediately before forming the material into a lap, in which way I obtain a very even sheet, which, when 25 applied in that condition to a carding-engine, 30 will produce a very even sliver.

The nature of my improvement and the manner in which the same is or may be carried into effect will be understood by reference to the 40 accompanying drawings, in which I have represented an automatic oiler applied in accordance with my invention to a two-section compound opener-lapper.

Figure 1 is a side elevation, and Fig. 2 is a 45 plan, of the machine.

The machine in its general organization requires but brief description.

A is the feed-apron; B, the whipper; C, the fan or dust-trunk containing the wire-cage

screens, between which the material passes on 50 its way to the beater D. E is the second fan or dust-trunk, and F are the calender-rolls. It is at or just beyond this point that I in this machine oil the sheet of fibrous material—that is to say, after it has passed the beater and 55 immediately before it is wound into a lap. For this purpose it will be found convenient to use an automatic oiler of any approved construction. An automatic oiler adapted for the purpose is represented in the drawings. It consists of a dripper, a, mounted in bearings on the machine-frame or on the oil-trough b. The shaft on which the dripper is fixed is a rock-shaft, moved in one direction by a cam and in the other by a spring. Pivoted to a suitable 60 point on some fixed part of the machine is a lever, c, connected by a strap, d, with the dripper-shaft, the strap taking a turn around the shaft, so that when the lever is moved back the strap will, by drawing on the dripper-shaft, 65 cause the dripper to turn back and down into the oil-trough. The lever is provided with a laterally-projecting stud and friction-roller, e, resting against the periphery of a revolving cam, f, which obtains its movement from the 70 gear g on one of the rotating wire-cage screens through the operation of gear h, compound gear i, j, and gear k, the latter being fast on the axle of cam f. A spiral spring, l, encircling the dripper-shaft, and fastened at one end to 75 the shaft and at the other end to some part of the dripper-frame which rocks on said shaft, acts to depress the dripper and holds the lever-stud e against the cam. When the machine is in movement the dripper is alternately 80 rocked backward, so as to be immersed in the oil in the trough, and then forward to the position indicated in the drawings, dropping suddenly (owing to the form of the cam) during 85 the latter part of the forward and downward movement, and thus throwing off a spray of oil, which falls upon the sheet of fibrous material beneath. The sheet is thus oiled uniformly and evenly after passing the beater and 90 immediately before being wound into a lap. 95

In conclusion, I state that I do not claim, broadly, administering oil to wool or other fibrous material after it has passed an opening

device and before it has been delivered to a carding-engine. This may be done without obtaining the result which I have in view, for I find in my experience that it is impracticable to collect the fibrous material into a sheet or lap that would be even enough to be of any practical advantage in going to the carding-engine if it should pass any beater or other opening device after having been oiled.

10. What I claim, and desire to secure by Letters Patent, is—

In a machine for opening fibrous material,

the combination, with the first and other beaters and the lapping device, of an oiler arranged and operating to administer oil to the 15 fibrous material after it has passed the said beaters and immediately before it is wound into a lap, as and for the purposes set forth.

In testimony whereof I have hereunto set my hand this 18th day of October, 1880.

WILLIAM ED. WHITEHEAD.
